UNITED STATES PATENT OFFICE.

MAX MANNESMANN, OF REMSCHEID, GERMANY.

MANUFACTURE OF SEAMLESS TUBES.

SPECIFICATION forming part of Letters Patent No. 361,959, dated April 26, 1887.

Application filed April 1, 1887. Serial No. 233,244. (Model.) Patented in Belgium August 14, 1886, No. 54,857.

To all whom it may concern:

Be it known that I, MAX MANNESMANN, of Remscheid, Germany, have invented certain Improvements in the Manufacture of Iron 5 or Steel Tubes, of which the following is a specification.

This invention relates to a process of and apparatus for successively performing the two operations, first, of forcing a solid steel or iron 10 blank which has been suitably heated to assume the form of a tube, and, secondly, of enlarging the size of the tube so formed.

The apparatus consists, essentially, of a pair of approximately barrel-shaped rolls, the vertical planes of the axes of which are arranged 15 upon opposite sides of the axial line of a conical or conoidal mandrel, with their axes inclined relatively in opposite directions. The conical or conoidal mandrel projects part way 20 between the rolls, and is slightly less acute than the angle of divergence of the tapering ends 25 of the rolls between which it is placed. A solid blank fed into the end of the space between the rolls opposite that into which the conical or conoidal mandrel projects is first 30 transformed into a tube by the action upon it of the converging working-faces of the rolls, according to the method described in the pending application of Max Mannesmann, serially numbered 227,087. The tube thus formed is 35 by the continued action of the rolls carried against and over the surface of the mandrel, upon which it is compressed by the diverging portions of the working-faces of the rolls, and is thereby made to acquire an increase in both 40 internal and external diameter, with such thickness of shell as may result from the distance between those portions of the working-faces of the rolls which are nearest to the surface of the mandrel.

The employment of approximately barrel-shaped rolls in combination with a conical mandrel for transforming a solid blank of soft metal into a tube of larger diameter than the 45 width of the narrowest part of the space between the working-faces of the rolls is described in Max Mannesmann's pending application, serially numbered 233,247; but in that case the pointed end of the mandrel is permitted to touch or nearly touch the central 50

portion of the blank, to which there is no objection when operating upon comparatively soft and ductile metals or alloys, but which is fatal to the practical, successful working of the apparatus when employed to operate on 55 iron or steel blanks which are required to be so highly heated to fit them to be operated upon that the pointed end of the mandrel would be destroyed were it permitted to come in contact with the interior portion of the blank. In 60 the present case, therefore, the rolls are so proportioned and adjusted that the tubular formation is fully developed by the preliminary action of the rolls, so that as the blank progresses the point of the mandrel enters 65 into an aperture in the center of the blank of such considerable diameter and length that the pointed end of the mandrel is not brought near enough to the hot metal to be destroyed. It will therefore be understood that the present 70 invention does not embrace, broadly, the combination of barrel-shaped rolls with a conical mandrel for the purpose of transforming a solid blank into a tube, and then enlarging the tube 75 thus formed, but consists in such a combination of barrel-shaped rolls and a conical mandrel that by the preliminary action of the rolls the tubular formation is fully developed from the solid blank before the tube-enlarging operation is commenced.

As diagonal rolling-machines are well known, it is deemed sufficient to herein show and describe only those portions of the apparatus which in their construction and mode of operation are comprehended in the present 85 invention.

The drawings are as follows: Figure 1 is a top view of a pair of barrel-shaped rolls, the axes of which are inclined in relatively opposite directions from the horizontal plane 90 of the axis of a conical mandrel projecting into the space between the rolls; also showing in horizontal section a solid metallic blank which has so far progressed into the space between the rolls at the end opposite to that into 95 which the mandrel projects that its forward portion has acquired a tubular formation. Fig. 2 is a top view of the apparatus, similar to that shown in Fig. 1, but representing the blank at a further stage of its progress, at which the 100

shell of the tubular formation has begun to be compressed upon the surface of the mandrel. Fig. 3 is a similar view of the apparatus, showing the fully-formed enlarged tube issuing at the end of the space between the rolls into which the conical mandrel projects.

For the sake of clearness of description, it is assumed that the two barrel-shaped rolls A and a (shown in the drawings) are arranged on either side of the axial line of a conical or conoidal mandrel, B, the axis of which is horizontal, and that the vertical planes of the axes of the rolls are parallel with each other and with the axial line of the mandrel, but are inclined from the horizontal plane in relatively opposite directions to such an extent as to approximately proportion the stretching effect which they exert upon the blank, owing to the diagonal direction in which they act, to the amount of reduction of the diameter of the blank which is effected during its passage between the converging portions A' and a' of the working-faces of the rolls for the purpose of developing in the portion of the solid blank C, upon which their preliminary action takes place, a tubular formation according to the method described in the said pending application of Max Mannesmann, serially numbered 229,087.

By the preliminary action of the rolls upon the blank the tubular formation C is fully developed in the forward portion of the blank by the time it has progressed far enough to acquire contact with the surface of the mandrel, in consequence of which, as will be seen, the pointed end of the mandrel enters an aperture of considerable diameter, and is thereby prevented from touching the hot blank. As the blank continues its progress, its shell is gradually diminished in thickness by compression between the surface of the mandrel and the diverging portions A' and a' of the working-faces of the rolls, which also act, respectively, in relatively opposite diagonal directions and co-operate with the converging portions A' and a' of the working-faces of the rolls in imparting the endwise movement to the metal of the blank by which it is carried over the base of the conical mandrel and transformed into a tube, C', the interior diameter of which is determined by the diameter of the largest part of the mandrel, and the thickness of the shell of which is determined by the distance between the largest part of the mandrel and the adjacent portions of the working-faces of the rolls, respectively.

When there is a suitable reduction in the thickness of the shell of the tube during the enlarging process, the entire blank can be transformed into a tube of uniform diameter from end to end. If, however, there is not a sufficient reduction in the thickness of the shell during the process of enlargement, or if from any other cause the diverging portions of the working-faces of the rolls cannot force the rear end of the blank over the mandrel,

such portion of the metal as may remain upon the mandrel at the conclusion of the enlarging process may be cut off, in which case the remaining product will be a tube of uniform size from end to end.

By the term "barrel-shaped" roll it is herein intended to include any roll the working-face of which is between two bearings, and which is so varied in its diameter that when two such rolls are placed on opposite sides of the path through which the blank travels, with their axes relatively inclined in opposite directions, the immediately-opposed portions of their working-faces are convergent from the end into which the blank is fed toward the point between the ends where the working-faces of the rolls most nearly approach each other, and from that point are divergent to the opposite ends of the rolls. It is also to be understood that, for the purposes of the invention, the mandrel may have its sides either concavely or convexly curved in the direction of its length, the only essential being that it shall have such a taper as will suitably provide for the amount of reduction in the thickness of the shell to be produced by the compression of the shell upon the surface of the mandrel.

What is claimed as the invention is—

1. The improvement in the art of transforming solid steel or iron ingots or blanks into tubes of prescribed internal and external diameter herein described, which consists in first progressively developing a tubular formation in a suitably-heated steel or iron blank by means of the action upon it of the converging portion of the working-faces of diagonally-acting barrel-shaped rolls so proportioned and adjusted as to the relatively opposite angles of inclination of their axes and as to the angles of convergence of the portions of their working-faces, which act preliminarily upon the blank, as to rupture the blank along the line of its axis and induce a spirally-outward movement of the metal from the center of the blank, and then, secondly, progressively compressing, and at the same time forcing forward, the shell of the tubular formation thus developed over the surface of a conical or conoidal mandrel by means of the external action upon the blank of the diverging portion of the working-faces of the said barrel-shaped rolls, between which diverging portions of the rolls the conical or conoidal mandrel is interposed, whereby at a single passage between the rolls a suitably-heated iron or steel blank is transformed into a tube the external diameter of which is greater than the width of the narrowest part of the space between the working-faces of the rolls.

2. In apparatus for transforming solid steel or iron blanks into tubes, diagonally-acting barrel-shaped rolls so arranged with relation to each other that the portions of their working-faces which first act upon the blank have convergent lines of impingement thereon, for

the purpose of fully developing a tubular formation in the portion of the blank upon which they act, and have the remaining portions of their working-faces divergent and combined with an interposed conical or conoidal mandrel for the purpose of progressively compressing the shell of the tubular formation upon the surface of the said mandrel, and thereby enlarging the internal and external diameter of said tubular formation to a prescribed extent.

MAX MANNESMANN.
